UNITED STATES PATENT OFFICE.

EMIL WENZEL, OF AUE, GERMANY, ASSIGNOR TO THE FIRM: ERNST GEßNER,
AKTIENGESELLSCHAFT, OF AUE, ERZGEBIRGE, GERMANY.

DRYING DEVICE FOR TUBULAR FABRICS.

Application filed June 6, 1925, Serial No. 35,406, and in Germany June 20, 1924.

This invention relates to a drying device for tubular fabrics, such as are produced on circular knitting frames from artificial silk, cotton or woolen yarns, and its object is to facilitate the drying of such tubular fabrics after dyeing or washing. The length of the pieces are usually about forty metres.

It has been hitherto customary in drying such tubular lengths to pass the tubular fabric in a stretched state over a hollow frame, so as to embrace the frame, whilst drying air, preferably suitably heated, is introduced to the space enclosed by the tubular fabric, which is dried by the passage of the air from the interior of the tube through the stretched walls of fabric. The tubular fabric, after treatment in the dyeing vats or the like is inserted in tubs and is threaded over the supply pipe for the drying fluid. The stretching frame is then placed over the mouth of the said supply pipe and the fabric tube passed over the frame so as to embrace it. This is a long and tedious operation and by means of the present invention it is possible to dispense with the operation of threading the tubular fabric over the supply pipe for the drying fluid.

The object of the present invention is to provide a form of drying device for such tubular fabrics, so arranged that the process is less onerous and more nearly continuous.

According to this invention the wet tubular fabric is threaded concentrically into a removable annular tub or container as it is taken from the dyeing vat or the like and this removable container is located centrally over a supply pipe for drying fluid and under the stretching frame whilst the latter is being supported by lateral supports which are then removed and their place taken by central supports for the stretching frame, whereupon the tubular fabric is threaded over the frame to embrace the same and be drawn thereover by means of draw rolls in the known manner.

The invention is illustrated by way of example in the accompanying drawings, in which—

Figure 1 is a sectional elevation of a drying device in accordance with this invention, and

Figure 2 is an elevation at right angles to that shown in Figure 1, part of one of the

standards being removed to reveal the lower mechanism of the device.

In carrying the invention into effect, the apparatus comprises two frame standards A which act as supports for the feed rolls o and the lateral support claws h, which in the form shown are carried by spindles h¹, 60 which may be moved radially inwards, as indicated by the small arrows.

The drying frame comprises a number of rings a, suitably supported from a central spindle b, which is fixed in the hub of a spider a², which carries the bottom ring a of the series. From the bottom upwards the rings a are conveniently of increasing diameter, but the top frame a⁴ is preferably adjustable in the axial direction of the feed rolls o, but, as can be seen in Figure 2, is narrower than the other frame rings. The adjustment of the top frame piece a⁴ is conveniently effected by supporting it on links a¹, which are adjustable as at a⁵. The circumferential supporting claws h are conveniently located opposite the widest frame ring, which, as shown, is conveniently double, so as to prevent binding at the turn from the larger to the smaller size of the frame bars a⁴.

The bottom spider a² is conveniently provided with centering dogs a⁸, which nest inside the central support. The central supporting member c is associated with the annular tub k, containing the wet length of tubular fabric. This association may be of any convenient form, but in the form illustrated the central support c is a cylindrical structure separate from the tub, and guided in an opening of the frame d, which supports the tub. The cylinder c is slidable in this central opening, and has conveniently diametrically opposite tooth racks f, arranged longitudinally on its circumference. These racks engage pinions e², which are operated from a hand-wheel e¹ and worm shaft e. By this mechanism the central support c may be raised or lowered as desired. The supply pipe for the drying air opens into the interior of the cylindrical central support c, by which it is conducted to the space enclosed by the tubular fabric stretched on the frame bars a.

The annular tub k is preferably suitably supported from the frame d and may, as

shown, be rotatable on this support by mounting the rollers m on the support and on which the tub rests. The rollers m may be grooved and a ring or roll m^1 on the bottom of the tub k may take into the grooves, so that the tub is supported centrally in respect to the axis of the drying device.

The figures show the parts in their working position. The fabric is drawn upwards from the tub k over the ring frame, being increasingly stretched over successive frame members, and then passed over the adjustable stretching frame member a^4 to be gripped in the feed rolls o . When the length of tubular fabric has passed from the annular tub k over the frame, the lateral supporting claws h are moved to support the frame in its central position, and the central support c is lowered by the hand wheel e^1 so as to enable the annular tub k to be removed sidewise, and the full tub inserted. The central support c is then again raised and the lateral supports h moved out of operation, whereupon the new length is threaded over the frame, and the process resumed.

I claim:—

1. A drying and stretching device for fabric in tubular form having in combination, 30 a stretching frame over which the fabric is passed so as to embrace the frame, a removable annular container into which the fabric tube is concentrically threaded, central 35 and lateral supporting means for said

stretching frame, means for rendering one or other of said supporting means operative as desired, a central supply pipe for drying fluid to the interior of said stretched tubular fabric and means for drawing the 40 fabric tube over the stretching frame.

2. In combination with draw rolls and a stretching frame for tubular fabrics, an annular container for the tubular fabric located at the opposite end of said frame from 45 the draw rolls and a hot air supply pipe opening centrally within said annular container, said annular container being removable laterally in respect to said frame and supply pipe.

3. A drying device for fabric in tubular form, having a loose and removable annular tub for the wet tubular fabric, a stretching frame located centrally over said tub, and composed of ring members which impart increasing stretch to the tubular fabric passed thereover, and an upper adjustable frame member, feed rolls located over said frame and receiving the fabric passed thereover, a central support for said frame located 55 below the same and co-axially with the annular removable tub, said support being adapted to be raised and lowered, lateral supporting members for said frame, means for rendering said lateral supporting members operative or inoperative as desired, and a supply pipe for drying air leading to the centre of said annular tub, substantially as and for the purposes described.

EMIL WENZEL.
